(57) **CLAIM**

The ornamental design for a bus shelter with integrated electronic display kiosks, as shown and described.

DESCRIPTION

FIG. 1 is a front perspective view of the bus shelter with integrated electronic display kiosks;

FIG. 2 is a front elevation view of the FIG. 1 device;

FIG. 3 is a rear elevation view of the FIG. 1 device;

FIG. 4 is a right side elevation view of the FIG. 1 device;

FIG. 5 is a left side elevation view of the FIG. 1 device;

FIG. 6 is a top view of the FIG. 1 device; and,

FIG. 7 is a bottom view of the FIG. 1 device.

The broken lines depict portions of the bus shelter with integrated electronic display kiosks that form no part of the claimed design.

1 Claim, 5 Drawing Sheets
